DESIGN FOR A COMBINATION FOOD-SERVING DISH

Benjamin F. Taylor, Pontiac, Mich.

Application February 15, 1936, Serial No. 61,181

Term of patent 7 years

To all whom it may concern:

Be it known that I, Benjamin F. Taylor, a citizen of the United States, residing at 197 Oliver street, City of Pontiac, in the county of Oakland, State of Michigan, have invented a new, original, and ornamental design for Combination Food Serving Dishes, of which the following is a specification, reference being had to the accompanying drawing, forming part thereof.

Figure 1 is a top plan view of the combination food serving dish, showing my new design;

Figure 2 is a view in side elevation; Figure 3 is a view in vertical mid-section; and Figure 4 is an enlarged fragmentary sectional view taken on line 4—4 of Fig. 1.

I claim:

The ornamental design for a combination food serving dish as shown.

BENJAMIN F. TAYLOR.
